UNITED STATES PATENT OFFICE.

JOHN F. STANDISH, OF WINTHROP, MASSACHUSETTS, ASSIGNOR TO UNITED SHOE MACHINERY CORPORATION, OF PATERSON, NEW JERSEY, A CORPORATION OF NEW JERSEY.

HEELING-MACHINE.

1,365,802.

Specification of Letters Patent. Patented Jan. 18, 1921.

Application filed February 23, 1918. Serial No. 218,763.

To all whom it may concern:

Be it known that I, JOHN F. STANDISH, a citizen of the United States, residing at Winthrop, in the county of Suffolk and State of Massachusetts, have invented certain Improvements in Heeling-Machines, of which the following description, in connection with the accompanying drawings, is a specification, like reference characters on the drawings indicating like parts in the several figures.

This invention relates to heeling machines and, more particularly, to the equipment of such machines with provision for attaching rubber, or other cushion, heels.

In attaching a cushion heel in a heeling machine, where the heel is necessarily subjected to a considerable degree of pressure, it is desirable that the heel be held in a rigidly immovable holder or form of considerable depth, to prevent distortion of the heel by the pressure and movement of the nail holes in the heel out of register with the holes in the nailing die through which the attaching nails are driven into the heel. Rubber heels, however, are usually of only moderate height and, inasmuch as the heads of the attaching nails are driven deeply into the heels, the nails used for this work are short. The presence, therefore, of a deep heel form upon the nailing die prevents a sufficiently close approach of the loader block, which delivers the nails to the die, to insure that these short nails shall enter the holes in the die.

One object of the present invention is to overcome the difficulty above outlined and, with this end in view, a feature of the invention consists in the combination with a nailing die and a loader block movable over and in close proximity to the die, of a rigid heel holder movable from an initial position over the die to a position at one side of the die, to permit the loader block to be moved into the space initially occupied by the holder. In order to permit both the loader block and the heel holder to occupy, alternately, a position over, and close to the upper surface of, the die, they may conveniently be arranged to move in substantially the same plane, the holder being in the path of movement of the loader block into nail delivering position, whereby the loader block, in its movement into such position, will engage

the holder and push it to one side, out of register with the die. Suitable means such, for example, as a spring, may be provided to return the holder to heel attaching position after the loader block is retracted.

In attaching rubber heels there is a much greater tendency to displace the heel form, or holder, than when leather heels are being handled. This results from the yielding nature of the rubber heel, which causes the holder to shift when the attaching pressure is applied. In this aspect of the invention, another feature thereof resides in the provision, in a heeling machine having a movable heel form or holder, of a locking member so directly connecting the holder to a relatively fixed portion of the machine that it is immovably held in heel attaching position. The locking means is preferably arranged to release the holder automatically under the control of the loading mechanism at the proper time to permit the holder to be moved away from attaching position. In the embodiment of the invention hereinafter described, an element of the locking mechanism is located in the path of the loader block, and is automatically actuated to release the form prior to the engagement of the latter by the block.

It is frequently desired to use the same machine, at will, for attaching either rubber or leather heels. In this connection, another feature of the invention consists in the provision of a special holder movable during the operation of the machine, which may be used in rubber heel attaching, constructed to permit easy, and instant removal, without the use of tools, whereupon the regular holder for leather heels may be placed upon the machine for use in the ordinary manner.

The invention further provides a heel holder normally occupying a heel attaching position upon the nailing die, but arranged to be moved away from the die and locked in a position where it will not interfere with the changing of dies for different nailings. After the change of dies has been made it is simply necessary to withdraw a locking pin to permit the holder to resume its operative position. This feature may be advantageously combined with a holder consisting of a form carrier constructed to accommodate any one of a series of removable and interchangeable form members fitting heels of

different sizes and shapes. The locking pin 5 may advantageously coöperate with a stationary stop which serves the double function of securing the holder in position away from the die while dies are being changed, and limiting the movement of the holder away from the die, under the impulse of the loader block in ordinary operation.

These and other features of the invention 10 will best be understood and appreciated by reading the following detailed description in connection with the accompanying drawings illustrating one embodiment thereof, though it should be understood that various features 15 of the invention might be embodied in other specific forms of construction without departing from its spirit and intent.

The term "loader block" is used throughout the specification and claims in a generic 20 sense, to denote any suitable form of device for carrying a load of nails to, and depositing them in, the nailing die.

In the drawings,

Figure 1 is a perspective view of one embodiment of the invention as seen from the front and left;

Fig. 2 is a similar view from the rear and left;

Fig. 3 is a similar view from the front 30 and right;

Fig. 4 is a vertical, longitudinal section from front to rear; and

Fig. 5 is a perspective view of a detail of the locking mechanism for the holder.

Referring now to the drawings, 10 indicates the driver head and 12 the nail drivers of a heelng machine; and 14 indicates a pair of side rods carrying the nailing die supporting member 16. The general construction and arrangement of these parts is substantially the same as in the machine disclosed in Patent No. 1,157,688, granted Oct. 26, 1915, upon the application of L. L. Glidden, to which patent reference may be 45 had for a full disclosure of the construction and operation of those features of a heelng machine with which the present invention is not concerned.

The nailing die, through which the 50 drivers 12 pass to drive the heel attaching nails, is shown at 18. In accordance with the usual practice, the nailing die is made of a standard size and is readily removable from the support 16 by simply turning up 55 the buttons 20 and drawing the die forwardly out of its seat in the support. Other standard or interchangeable dies, may thus be easily substituted to produce a nailing of any desired size or shape.

60 The rear portion of the nailing die support 16 is bored out to receive the reduced end 22 of a cylindrical guide bar 24, which is supported rigidly in a horizontal position in a suitably formed trough or groove 26 65 extending along the rear of the die support.

28 indicates a heel form carrier having a rearwardly extending portion 30 which is bored out to fit, but slide freely upon, the guide bar 24. One end of a tension spring 32 is anchored upon a pin 34 inserted in a bracket 36 extending from the side of the die support 16. The opposite end of the spring is secured in a lug 38 projecting from the form carrier. This spring is always under tension and tends to draw the form carrier toward the right, as seen in Figs. 1 and 3, normally holding it with the end of the member 30 in engagement with an adjustable stop 40 secured by a bolt and slot connection to the portion 42 of the nailing die 80 support 16.

The form carrier is provided with guides in which may be removably secured a heel form member 44 of considerable depth and shaped to fit the heel to be attached. An interchangeable series of these form members is provided to accommodate all the different sizes and shapes of heels to be handled. The form member is secured in position in the carrier 28 by a pin 46, which is normally held in securing position by a spring 48 but which may be readily withdrawn to permit the changing of forms. When the form member 44 is secured in the carrier 28 and the stop 40 properly adjusted, the heel holder, comprising the form carrier and form member, will normally occupy a position immediately over the nailing die 18, in which the nail holes in the rubber heel 50 will register with the holes in the nailing die, as clearly shown in Fig. 4.

In order to insure the heel form against any possibility of displacement when pressure is applied to the heel, means is provided for locking it immovably in heel attaching position. A latch 52, carried by the lower end of an upright shaft 54 journaled in a suitable bearing in the form carrier, is arranged to engage a pin 56 mounted in a longitudinally adjustable plate 58 secured by a screw and slot connection to the die support 16. After adjusting the stop 40 to locate the heel form in precisely the right position, the pin 56 is adjusted to engage the hook 52 of the locking member upon the form carrier. The hook 52 is held in engagement with the pin 56 by a torsion spring 60 surrounding the shaft 54. One end of the spring bears against the flange 62, which is a part of the form carrier, and the other end is bent around an arm 64 secured to the upper end of the shaft 54. By swinging the arm 64 in a clockwise direction the spring 60 will be caused to yield and the latch 52 will be moved out of locking engagement with the pin 56, permitting the form carrier to be moved toward the left against the tension of the spring 32.

The front end of the form carrier extends downwardly in front of the nailing 130

die and die support, as shown at 66. A slot 68 is formed in the inner face of the extension 66 and is properly located to engage a roll 70 rotatably mounted upon a stud 72 secured in the nailing die support 16 by a set screw 74. The end of the slot 68 is curved upwardly at 76. The slot 68 in the extension 66 and the roll 70 constitute guiding bearings for the front of the form carrier, which is guided at the rear by the bar 24. Inasmuch as the guide bar 24 is cylindrical, the form carrier may have both a longitudinal sliding movement and a swinging movement about the axis of the bar. This swinging movement is effected by the curved portion 76 of the slot 68, and its purpose is to force the form carrier down closely upon the die when the form is in heel attaching position, but to cause it to be raised slightly from the upper face of the die and die support as it is moved away from heel attaching position, thus avoiding friction and possible interference with the movement of the holder by dirt, which frequently accumulates on the top of the die and die support.

The nails are supplied to the nailing die prior to the heel attaching operation by the loader block 80, which is mounted to swing about the vertical stud 82 and moves in substantially the same plane as the heel holder, that is to say, as close as possible to the top of the nailing die and its support. It is important that the loader block approach as closely as possible to the surface of the nailing die, since the nails used for attaching rubber heels are usually quite short and must be guided practically continuously while they are being delivered from the loader block to the nailing die.

A flattened portion 84 upon the end of the arm 64 of the locking device is arranged in the path of the loader block 80. As the loader block is swung toward the nailing die, it engages first the said flattened member 84, swinging the latch 52 out of engagement with the pin 56 and unlocking the heel holder. Further movement of the loader block causes the flattened member 84 to engage a suitably formed and located lug 86 projecting from the flange 62, transmitting the motion of the loader block to the form carrier, which slides toward the left away from its normal heel attaching position over the nailing die. After the load of nails has been delivered to the nailing die, the loader block is retracted, the spring 32 promptly drawing the heel holder back to its normal position over the die, and the hook 52 automatically locking the holder in position ready for the heel attaching operation.

A lug 90, projecting from the upper face of the nailing die support, lies in the path of a pin 92 which slides vertically in a bearing 65 in the form carrier and is normally de-

pressed by a spring 94. In the normal operation of the machine the face 96 of the lug 90 acts as a stop to prevent the heel holder from moving too far to the left under the impulse imparted to it by the loader block. When it is desired to change nailing dies, the heel holder may be moved manually to the left, the pin 92 being withdrawn to permit it to pass over the lug 90 and then released, whereupon the pin will engage the opposite face 98 of the lug, securing the holder in a position away from over the die where it will not interfere with the changing of the dies.

An important advantage of the present invention is the ease with which the heel holder may be removed from the machine, leaving the machine ready for the reception of the usual holder for ordinary leather heel work. It is only necessary to slip the end 80 of the spring 32 off the pin 34 and raise the spring pressed pin 92 to allow it to pass the lug 90, whereupon the form carrier with its form member and locking mechanism may easily be slid bodily off the end of the guide 85 bar 24. This operation can be performed in an instant and requires no tools whatever.

Having described my invention, what I claim as new and desire to secure by Letters Patent of the United States is:—

1. In a heelng machine, the combination of a nailing die, a loader block movable over, and in close proximity to, the die, and a rigid heel form movable from an initial position over the die to a position at one side 100 of the die, to permit the loader block to be moved into the space initially occupied by the form.

2. In a heelng machine, the combination, with a horizontally stationary nailing die, 105 of a loader block and a heel form movable, in substantially the same plane, alternately into nail delivering and heel attaching positions, respectively, relatively to the die, the construction and arrangement being such 110 that movement of the heel form is effected by movement of the loader block.

3. In a heelng machine, the combination, with a nailing die, of a loader block movable to a nail delivering position over, and in 115 close proximity to, the die, and a heel form normally occupying a position over the die in the path of the loader block and movable, by engagement of the loader block with the form, to a position at one side of the die. 120

4. In a heelng machine, the combination, with a nailing die, of a loader block movable to a nail delivering position over the die, a heel form normally occupying a position over the die in the path of the loader block 125 and movable, by engagement of the loader block with the form, to a position at one side of the die, and means for returning the form to initial position when the loader block is retracted.

5. In a heelng machine, the combination, with a nailng die, of a heel form or holder movable into and away from a heel attaching position relatively to the die, and a locking member directly connecting the holder with a relatively fixed portion of the machine to retain said holder immovably in said heel attaching position.
6. In a heelng machine, the combination, with a nailng die and loading mechanism therefor, of a heel form or holder movable into and away from a heel attaching position relatively to the die, means for locking the holder immovably in heel attaching position, and means controlled by the loading mechanism for actuating the locking means automatically to release the holder prior to its movement away from attaching position.
7. In a heelng machine, the combination, with a nailng die, of a loader block movable into and away from a nail delivering position over the die, a heel form or holder movable into and away from a heel attaching position over the die, and means for locking the holder immovably in heel attaching position, an element of said locking means being located in the path of the loader block, whereby movement of the latter toward nail delivering position causes the heel holder to be released.
8. In a heel attaching machine, the combination, with a nailng die, of a heel form or holder normally occupying a heel attaching position in relation to the die and movable into and away from said position during the operation of the machine, and constructed and arranged to permit easy removal from the machine without the use of tools.
9. In a heel attaching machine, the combination, with a nailng die, of a heel form or holder movable under the control of an element of the machine into and away from a heel attaching position in relation to the die, and constructed and arranged to permit instant bodily removal from the machine.
10. In a heel attaching machine, the combination of a nailng die support, a nailng die removably mounted in said support, a heel holder normally occupying an operative position upon the die but movable to an inoperative position away from the die, and means for locking the holder in said inoperative position to permit the changing of dies without interference by the holder, said locking means being manually releasable to permit the holder to resume its operative position.
11. In a heel attaching machine, the combination of a nailng die support, a nailng die removably mounted in said support, a heel holder movable into and away from a position upon the die, a removable, heel fitting, form member in the holder, and locking means for securing the holder in position away from the die to permit the changing of dies without interference by the holder.
12. In a heelng machine, the combination, with a nailng die, of a heel holder movable from a heel attaching position over the die to a position away from the die, a stop member, and a locking member, carried by the holder, coöperating with one part of the stop member to limit the movement of the holder away from the die, and with another part of the stop member to secure the holder in a position away from the die.
13. In a heelng machine, the combination, with a nailng die, of a heel holder movable from a heel attaching position over the die to a position away from the die, a stationary stop member, and a spring pressed locking pin, carried by the holder, coacting alternatively with one side of the stop member to limit the movement of the holder away from the die and with the other side of the stop member to secure the holder in a position away from the die.

In testimony whereof I have signed my name to this specification.

JOHN F. STANDISH.
